UNITED STATES PATENT OFFICE.

EARL P. OSWALD, OF DETROIT, MICHIGAN, ASSIGNOR, BY MESNE ASSIGNMENTS, TO THE HOOVER COMPANY, OF NORTH CANTON, OHIO, A CORPORATION OF OHIO.

REFRIGERATING APPARATUS.

Application filed August 21, 1920. Serial No. 405,009.

To all whom it may concern:

Be it known that I, EARL P. OSWALD, a citizen of the United States, residing at Detroit, county of Wayne, State of Michigan, have invented a certain new and useful Improvement in Refrigerating Apparatus, and declare the following to be a full, clear, and exact description of the same, such as will enable others skilled in the art to which it pertains to make and use the same, reference being had to the accompanying drawings, which form a part of this specification.

This invention relates more particularly to cooling coils for refrigerating systems, the principal object of which is to provide a cooling coil having what is known as a sharp freezing chamber in conjunction therewith in which the temperature is maintained practically at the predetermined point irrespective of variations in temperature in the storage compartment within which the coil is positioned. A further feature of the invention is involved in the construction of a coil wherein a portion thereof is exposed to the atmosphere of the compartment to be cooled and a portion of which is insulated from the atmosphere of the compartment. In artificial refrigerating systems heretofore known operating to hold the storage compartment at a temperature of about forty-five degrees F., a cooling coil is utilized in the storage compartment and in close proximity to the coil is provided a tray of some character having depressions or compartments for the freezing of water therein to provide ice for household use. Such devices as heretofore known are only partially successful in operation due to variations in temperature of the storage compartment, especially in such systems where the operation depends upon the temperature of the compartment. When the temperature has increased to a certain predetermined degree the motor is energized and the refrigerant medium is compressed and then expanded in the cooling coil and the absorption of the heat in the storage compartment and upon reduction of the temperature thereof to a predetermined degree causes cessation of operation of the system and as the storage compartment again becomes warmed the process is repeated. With such an apparatus as previously known the ice in the trays adjacent the cooling coil becomes melted

previous to the succeeding operation of the system. The apparatus herein disclosed is designed to prevent this subjection of the formed ice to variations in temperature of the storage compartment and to provide a chamber in which the temperature is maintained sufficiently low during the periods of non-operation of the system to prevent any partial melting of the ice. With these and other objects in view, I have provided a portion of the cooling coil so shielded from atmosphere of the storage compartment as to be practically wholly unaffected thereby during the periods of idleness of the refrigerating system and another portion thereof depended upon to cool the storage compartment thereby providing a definite part of the cooling coil for the performance of the specific function of freezing water and holding the same in frozen condition without variation in its character. These and other objects and novel features of the invention are hereinafter more fully described and claimed, and the preferred form of construction of apparatus embodying my invention is shown in the accompanying drawings in which—

Fig. 1 is a front elevation of a refrigerator showing the general relationship of the cooling coil and storage compartments.

Fig. 2 is a vertical section of the cooling coil indicating the construction thereof and in connection with which is diagrammatically shown the remaining parts of an artificial refrigerating system.

Fig. 3 is a detail in section showing the valve for the vacuum space of the coil body.

It is to be understood that this refrigerating system may be of any approved type either a brine circulating system or a system in which sulphur dioxide or other gas is used as a refrigerant medium. The system diagrammatically shown is of the latter type, and the motor, pump and compression coil may be located in any approved manner relative to the storage compartment either at the top or even remote therefrom as in some systems now in use. In any event the cooling coil 1 should be located in such manner that the atmosphere of the storage compartment is affected thereby preferably by placing the same within the compartment proper as is herein shown. It may, however, be placed in a separate compartment open to

the storage compartment in such manner that the air of the compartment may circulate through or about the cooling coil.

In my preferred form of construction the 5 cooling coil 1 is placed in the upper part of the storage compartment on one side thereof, which compartment is preferably divided into two parts by the dividing wall 2 having an opening 3 and 4 at the top and bottom 10 respectively so that air may pass downward in the compartment 5 in which the coil is located and upward in the compartment 6 through the aperture 3 to and in contact with the cooling coil where the air is cooled 15 and again pass downward in its circuit. In the diagram shown in Fig. 2, the pump and motor is indicated at 7, the discharge line of the pump connects with the compression coils 8 where the refrigerant is cooled from 20 which it passes through the usual expansion valve 9 to the cooling coil 1, and from thence by means of the pipe 10 to the intake side of the pump. The pump thus tends to maintain a minus pressure in the cooling 25 coil and expansion side of the system. In the apparatus illustrated a gas is utilized as a refrigerant, as for instance SO_2 , and the pressure maintained on the coils 8 will cause liquefaction of the same as soon as the temperature thereof is at normal atmospheric 30 temperature. The liquid on passing through the expansion valve 9 to the expansion side of the system where the pressure is relieved expands or boils and tends to absorb heat 35 from the surrounding atmosphere of the storage compartment and when the temperature of the coil is sufficiently reduced the refrigerant tends to liquefy in the expansion coil, especially during the period of idleness 40 of the system and advantage is taken of this liquefaction in the expansion coils by the construction hereinafter described.

In order that the cooling coil may be provided with a portion thereof to practically 45 so function as to maintain a certain temperature in the sharp freezing chamber and a portion thereof utilized to maintain the desired higher degree of temperature of the storage compartment I construct the cooling 50 coil as follows—I provide a receptacle like member 11 one end of which is open and provided with an external flange 12. Within the receptacle I place a similar member 13 having an external flange 14. On this inner member 13 I form a coil 15, the turns of 55 which are practically in contact with the outer surface of the member 13, the first or end turn of which is provided with a projection 16 extending through an aperture in 60 the outer member 11. At the opposite end I provide a similar outwardly extending end 17 of the coil to which is connected the outer coil 18 formed of a series of turns on the outside of the member 11. These turns of 65 the coil 18 may be slightly greater in inner

diameter than the diameter of the member 11 and thus slightly spaced therefrom to allow a comparatively free circulation of air through and about the exterior of the coils. The member 16 of the inner coil is connected 70 with the pipe line 19 leading from the expansion chamber 9 and the end of the coil 18 is connected by means of the pipe line 10 with the intake side of the pump 7. By this arrangement the two coils are in series and fluid passes from the expansion 75 valve first through the inner coil 15 and then through the outer coil 18 to the compressor. 80

With the ordinary household refrigerator of about eight or ten cubic feet I use copper tubing of about one-half inch diameter. The outer coil is about ten inches in diameter and fifteen inches in length and there is a space of about one inch between the walls of the outer and inner receptacles 11 and 13. Preferably, the space between the receptacles is practically exhausted of air and for this purpose the two flanges 12 and 14 have soldered thereto a ring member 21 closing the opening between the two receptacles. Also the apertures through which the portion 16 and 17 of the inner coil project are provided with a plate 22 and 23 respectively which is soldered in position and the tubes soldered in the respective plates. At a convenient 90 point I provide a valved conduit 24 similar to the valve stem of an inner tube of an automobile tire, the valve being positioned to close on outward pressure and to open on pressure from the interior. When the space between the members 11 and 13 has been sealed, I attach a pump to this member 24 and withdraw all the air possible whereupon, the valve being closed, the receptacle is sufficiently effectively sealed for all practical 95 purposes. Subsequent to the removal of the pump the chamber 25 formed by the interior receptacle is provided with a cover member of any approved type shown at 100 26 which is preferably hollow in form from the interior of which the air has been exhausted and thus providing an efficient insulating member for closing the receptacle 25 to the atmosphere of the storage compartment. As shown in Fig. 1 this cooling coil is positioned with the covered end toward one of the doors of the storage compartment so that upon opening of the door the cover member 105 26 is exposed and may be readily removed by hand. Within this chamber 25, which I 110 term the sharp freezing chamber, I provide any convenient device, as for instance a tray 27 having a series of depressions of the desired form therein in which water may be placed. Due to the low temperature 115 maintained within the sharp freezing chamber this water is soon frozen. The purpose of this peculiar construction of the cooling coil is to provide a portion thereof which is unaffected by variation in temperature of 120 125 130

the storage compartment. As heretofore stated, apparatus of this character in general is usually provided with a thermostatic switch device of some character causing cessation of operation of the compressor when a sufficiently low temperature has been attained in the storage compartment and the compressor is not set into operation until a certain predetermined increase of temperature takes place in the storage compartment.

In the usual household refrigerator utilizing artificial refrigerating apparatus, the temperature is maintained at from about 15 forty to fifty degrees F., which is a sufficiently high temperature to cause melting of ice if exposed to the atmosphere of the compartment as has heretofore been the case. By insulating a portion of the cooling coil and providing a sharp freezing chamber the atmosphere of which is affected by this insulated portion alone of the cooling coil, I secure a decidedly beneficial result in that the sharp freezing chamber 25 will remain for a considerable period of time below a freezing temperature and without any material change therein. With these systems as utilized for household use the period of operation of the compressor is 30 from about fifteen minutes to one half hour and the period of non-operation is for from about one hour to one and one half or two hours. It is therefore evident that the construction as outlined is sufficient to hold the 35 temperature of the sharp freezing chamber practically without change as the period of inactivity of the refrigerating system is for not more than a two hour period under normal conditions.

40 It is therefore to be seen that I have taken advantage of the principle involved in the well known vacuum bottle in common use for maintaining liquids at a certain temperature. The vacuum prevents the heat 45 of the storage compartment from affecting the temperature of the interior of the sharp freezing chamber. The construction, however, is superior to the vacuum bottle type of construction in that a cold medium is introduced in the vacuum space by which the 50 temperature of the sharp freezing chamber is controlled and maintained. The vacuum space shields the chamber as stated and also shields a portion of the expansion coil 55 which contains the refrigerant fluid and provides a portion of the coil in which liquefaction may take place (due to its temperature) when the apparatus is idle. When the apparatus is idle the fluid in the 60 portions of the expansion system exposed to atmosphere of the compartment may take up heat and become gasified causing a pressure in the expansion coil which assists in the liquefaction of fluid in the colder portion of the coil. By the construction out-

lined in which a portion of the coil is insulated from influence of the atmosphere of the storage compartment and in which liquefaction may take place as stated, I secure the further advantage that, upon the 70 starting of operation of the compressor after a period of inactivity, the compressor very soon begins to first cause the liquid to boil taking up the heat of the storage compartment almost immediately and sooner 75 than would be the case if the liquid had first to be transferred through the expansion valve. In fact soon after starting up the compressor begins to draw refrigerant in liquid form from this coil and the work 80 of the compressor is therefore reduced to a considerable degree.

As before stated this type of cooling coil may be utilized with various types of artificial refrigerating apparatus. If a brine 85 is to be circulated the benefits arising from liquefaction as stated when SO_2 is used does not pertain but all the other objects of the invention, however, would be obtained by this general construction of the cooling coil 90 particularly in that a portion of the cooling coil is insulated from influence of the atmosphere of the storage compartment and positioned to affect the sharp freezing chamber only. I therefore do not desire to 95 limit myself particularly to the character of the refrigerant utilized or to the general construction of the refrigerating system but to the cooling coil which may be of various shapes and sizes and may vary considerably in detail of construction within the 100 limitations of the appended claims.

What I claim is—

1. A cooling coil for artificial refrigerating systems comprising a double walled receptacle providing a central insulated chamber, said central chamber having a closable opening, a coil about the outer surface of the receptacle, and a coil between the inner and outer walls of the receptacle in 105 series with the outer coil.

2. A cooling coil for artificial refrigerating systems, comprising a double walled receptacle providing an insulated central compartment, and a coil forming part of the 110 circulation system of the apparatus positioned between the inner and outer walls of the receptacle.

3. In an artificial refrigerating system including a storage compartment and a circulating system for the refrigerant, a double walled receptacle within the compartment providing an insulated central chamber, a cooling coil having a portion thereof about the exterior surface of the receptacle 115 and a portion thereof between the inner and outer walls of the receptacle, the two portions being in series and the refrigerant fluid passing first to the interior coil and then to the exterior coil.

4. A cooling coil for artificial refrigerating systems comprising the combination with the storage compartment of the refrigerator, of a cooling coil formed of two parts, one of said parts being exposed to the atmosphere of the compartment, a vacuum chamber, the other of said parts being positioned within the vacuum chamber, and a freezing chamber enclosed by the vacuum chamber, the freezing chamber being provided with a closable opening.

5. In an artificial refrigerating system including a storage compartment, compression and expansion lines and thermostatically controlled apparatus for circulating the refrigerant, the combination therewith

of a cooling coil in the expansion line, said coil consisting of two parts in series, the first of the said parts beginning with the inlet end of the expansion line being wholly insulated or shielded throughout the length thereof from influence of temperature variations in the storage compartment, the said second part of the coil lying wholly exposed to influence of temperature change in the storage compartment, and a chamber subject only to the influence of the insulated portion of the cooling coil.

In testimony whereof, I sign this specification.

EARL P. OSWALD.
